[57] **CLAIM**

The ornamental design for a fan for internal combustion engines, as shown.

DESCRIPTION

FIG. 1 is a front elevational view of a fan for internal combustion engines showing my new design;
FIG. 2 is a rear elevational view thereof;
FIG. 3 is a side elevational view thereof, looking directly at the outer end of one fan blade; and
FIG. 4 is a side elevational view thereof, the fan being rotated approximately 30° from its position in FIG. 3.

Fig. 1.

Fig. 2.

Fig. 3.

Fig. 4.
